PISTON

Albert C. Notturno, Hewlett, N. Y.

Application August 14, 1942, Serial No. 454,841

6 Claims. (Cl. 123—78)

The present invention relates to new and useful improvements in pistons for engines and has for its primary object to provide an internal auxiliary piston within the main piston and having communication with the combustion chamber in which the main piston is mounted to provide greater expansion in the combustion chamber and thereby increase the power of the engine without necessitating an increase in size of the cylinder or main piston.

A further object is to provide an engine cylinder of this character of simple and practical construction, which is efficient and reliable in performance, relatively inexpensive to manufacture and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout and in which—

Figure 1 is a side elevational view of the main piston.

Figure 2 is a top plan view thereof.

Figures 3 and 4 are transverse sectional views taken respectively on the lines 3—3 and 4—4 of Figure 1.

Figure 5 is a fragmentary sectional view through the top of the piston taken substantially on a line 5—5 of Figure 2.

Figure 6 is a vertical sectional view taken substantially on a line 6—6 of Figure 1, and

Figure 7 is a similar view taken at right angles to Figure 6.

Referring now to the drawings in detail wherein for the purposes of illustration I have disclosed a preferred embodiment of the invention, the numeral 5 designates the main piston generally which includes a skirt portion 6 and top 7 connected to the upper end of the skirt portion by the threaded connection 8. The skirt portion 6 is provided with the usual piston rings 9.

Positioned in the skirt portion of the piston is a cylinder 10 open at each end and connected in concentrically spaced relation with the inner walls of the skirt portion 6 by means of web members 11.

In the upper edge of the cylinder 10 is an annular groove or channel 12 in which is fitted a packing ring 13 adapted to bear against the underside of the top 7 to seal the upper end of the cylinder 10.

An auxiliary piston 14 has a working fit in the cylinder 10 and is also provided with the piston

rings 15 in the upper portion of the skirt portion of the auxiliary piston.

The main piston 5 is provided with the usual wrist pin 16 to which the upper end of the connecting rod 17 is attached by means of the bearing 18 and projecting from the bearing 18 at a side thereof diametrically opposite from the connecting rod 17 is a pair of spaced parallel arms or lugs 19 between which the lower end of a short connecting rod 20 is positioned and pivotally attached thereto. The upper end of the connecting rod 20 is connected to the wrist pin 21 of the auxiliary piston 14 by means of the bearing 22.

The top 7 of the main piston is provided with a plurality of openings 23 to afford communication between the combustion chamber of the cylinder in which the main piston is working and the top of the cylinder 10 above the auxiliary piston 14.

20 A plurality of spring fingers 24 are attached to the underside of the top 7 by means of screws 25, the spring fingers having their end portions free and provided with laterally extending stems 26 having heads 27 at the ends thereof, the stems 26 and heads 27 working in the openings 23 to keep the openings free from accumulation of carbon deposits. The springs 24 are adapted to enter recesses 28 formed in the underside of the top 7 of the piston so as to prevent movement of the top of the auxiliary piston 14 flush with the top of the cylinder 10.

The stems 26 and heads 27 are considerably smaller than the diameter of the openings 23 to permit the free passage of gases through said openings.

35 In the operation of the device when the main piston 5 is descending on its intake stroke the auxiliary piston 14 also descends in an independent stroke and reaches the end of its downward stroke relative to the piston 5 when the connecting rod 17 is substantially at a 45 degree angle with respect to the crankshaft, as shown by the left hand dotted line position in Figure 7 of the drawings. When the main piston 5 has completed its stroke the connecting rod resumes its perpendicular position, thus moving the auxiliary piston 14 into its upward position. The same procedure is repeated on the upward stroke of the main piston 5. Accordingly, an increased charge of combustible is forced into the combustion chamber by the increase in the volume of the compression chamber of the main cylinder of the engine during its intake stroke, to admit a greater volume of fuel into the cylinder, and when 50 the auxiliary piston 14 completes its upward or

compression stroke, the additional mixture is forced back into the main cylinder through the openings 23, and compressed with the charge of the main portion of the combustion chamber.

It is believed the details of construction, advantages and manner of use of the device will be readily understood from the foregoing without further detailed explanation.

Having described the invention, what is claimed as new is:

1. A piston for explosive engines including a main piston, a cylinder in the main piston, an auxiliary piston working in said cylinder, a connecting rod for the main piston, a connecting rod for the auxiliary piston connected directly in line to the first named connecting rod for actuation of the auxiliary piston in accordance with the suction and compression strokes of the main piston and arranged to produce an increased number of suction and compression strokes of the auxiliary piston over that of the main piston, said main piston having an opening in its top, and means for cleaning said opening.

2. A piston for explosive engines including a main piston, a cylinder in the main piston, an auxiliary piston working in said cylinder, a connecting rod for the main piston, a connecting rod for the auxiliary piston connected directly in line to the first-named connecting rod for actuation of the auxiliary piston in accordance with the suction and compression strokes of the main piston and arranged to produce an increased number of suction and compression strokes of the auxiliary piston over that of the main piston, said main piston having an opening in its top, and means working in the opening for cleaning the latter.

3. A piston for explosive engines including a main piston, a cylinder in the main piston, an auxiliary piston working in said cylinder, a connecting rod for the main piston, a connecting rod for the auxiliary piston connected directly in line to the first-named connecting rod for actuation of the auxiliary piston in accordance with the suction and compression strokes of the main piston and arranged to produce an increased number of suction and compression strokes of the auxiliary piston over that of the main piston, said main piston having an opening

in its top, and means responsive to pressure in the cylinder for cleaning the opening.

4. A piston for explosive engines including a main piston, a cylinder in the main piston, an auxiliary piston working in said cylinder, a connecting rod for the main piston, a connecting rod for the auxiliary piston connected directly in line to the first named connecting rod for actuation of the auxiliary piston in accordance with the suction and compression stroke of the main piston and arranged to produce an increased number of suction and compression strokes of the auxiliary piston over that of the main piston, said main piston having an opening in its top, and a resilient member carried by the top of the main piston and working in the opening for cleaning the latter.

5. A piston for explosive engines including a main piston, a cylinder in the main piston, an auxiliary piston working in said cylinder, a connecting rod for the main piston, a connecting rod for the auxiliary piston connected directly in line to the first-named connecting rod for actuation of the auxiliary piston in accordance with the suction and compression stroke of the main piston and arranged to produce an increased number of suction and compression strokes of the auxiliary piston over that of the main piston, said main piston including a top closing the top of the cylinder and having an opening, and a cleaning device carried by said top and working in the opening.

6. A piston for explosive engines including a main piston, a cylinder in the main piston, said main piston having ports in its top providing for the admission and discharge of products of combustion into and out of said cylinder, an auxiliary piston working in the cylinder, a connecting rod attached to the main piston, and a connecting rod attached to the auxiliary piston and connected directly in line to the first-named connecting rod for actuation of the auxiliary piston in accordance with the suction and compression strokes of the main piston and arranged to produce an increased number of suction and compression strokes of the auxiliary piston over that of the main piston.
